CLAIM

The ornamental design for a handheld thermovision device as shown and described.

DESCRIPTION

FIG. 1 is a front, right-side perspective view of a handheld thermovision device embodying my new design;

FIG. 2 is a back, left-side perspective view of the handheld thermovision device of FIG. 1.

FIG. 3 is a front elevational view of the handheld thermovision device of FIG. 1.

FIG. 4 is a back elevational view of the handheld thermovision device of FIG. 1. FIG. 5 is a top view of the handheld thermovision device of FIG. 1. FIG. 6 is a bottom view of the handheld thermovision device of FIG. 1.

FIG. 7 is a right-side view of the handheld thermovision device of FIG. 1; and,

FIG. 8 is a left-side view of the handheld thermovision device of FIG. 1.

The dashed broken lines illustrate portions of the handheld thermovision device and form no part of the claimed design.

1 Claim, 8 Drawing Sheets
